UNITED STATES PATENT OFFICE.

SOLOMON G. LIPSCHUTZ, OF PHILADELPHIA, PENNSYLVANIA.

CIGAR-PRESSER.

942,397.

Specification of Letters Patent. Patented Dec. 7, 1909.

Application filed May 17, 1909. Serial No. 496,439.

To all whom it may concern:

Be it known that I, SOLOMON G. LIP-
SCHUTZ, a citizen of the United States, re-
siding at Philadelphia, in the county of
5 Philadelphia and State of Pennsylvania,
have invented certain new and useful Im-
provements in Cigar-Presses, of which the
following is a specification.

My invention relates to presses for pack-
10 ing cigars in boxes and consists in providing
in combination with a reciprocating plunger
press collapsible partitions that are slidably
mounted on the base and plunger, said parti-
tions being connected with operating mech-
15 anism to simultaneously actuate them to
gather the boxes into a compact mass before
compression and hold during compression.

The construction of my improved press
will be described in detail hereinafter and
20 illustrated in the accompanying drawings
in which—

Figure 1 is a side view of my improved
press, and Fig. 2, an end view.

In the drawings similar reference char-
25 acters indicate corresponding parts in both of
the views.

1 indicates the base of my improved press
to which is secured the pillars 2 supporting
the top 3.

30 4 indicates the plunger slidably mounted
on pillars 2 and actuated by means of screw
5 mounted in top 3 and rotatively secured
to the plunger 4, said screw being actuated
by hand wheel 6.

35 7 and 8 indicate angle iron bars slidably
mounted by means of dovetail tongues 7^a
and 8^a in dovetail grooves 9 in the upper
face of base 1 and dovetail grooves 10 in the
under surface of plunger 4 respectively.

40 11 indicates grooved pieces secured to
angle bars 7 and spaced apart thereon and
12 tongued pieces secured to bars 8, spaced
apart thereon and arranged in alinement
with the spaces between pieces 11.

45 It will be understood from this descrip-
tion that as the plunger 4 is moved up and
down on the pillars 2 the partitions formed
by pieces 11 and 12 extend and contract.

50 13 and 14 indicate brackets secured adj-
acent to the ends of plunger 4 and having
shafts 15 and 16 journaled thereon, said
shafts having arms 17 secured thereto that
are connected to angle bars 8 by means of
links 18. 19 and 20 indicate other arms se-
cured to shafts 15 and 16 respectively, and
21 a rod connecting said arms. It will be

understood from this construction that when
either shaft 15 or 16 is rocked the other shaft
is simultaneously rocked and the angle bars
8 are moved toward or away from each 60
other.

22 and 23 indicate shafts journaled adja-
cent to the ends of base 1 and having arms
24 secured thereto and connected to angle
bars 7 by means of links 25. 26 and 27 indi-
cate other arms secured to shafts 22 and 23,
respectively, and 28 a rod connecting said
arms to insure simultaneous rocking of the
shafts 22 and 23 when either of them is
rocked. 70

29 indicates a lever arm secured to shaft
15 and having a slot 30 therein and a handle
31 on its end; 32 an arm secured to shaft 22,
33 a rod pivotally secured to arm 32 and
slidably mounted in slot 30 in arm 29 and 75
secured to said arm by means of a pin 34
engaging alined holes in the arm and one
of a series of holes 35 in the rod 33.

In operation the plunger 4 is raised and
the cigars in boxes placed on base 1 between
the partitions formed by tongue and grooved
pieces 11, 12. When the boxes are in posi-
tion these partitions are moved toward each
other by securing pin 34 in the holes in arm
29 and one of the holes 35 in rod 33 and ac-
tuating the arm upwardly. This will rock
shafts 15 and 22 and through the arms 19
and 20 secured to shafts 15 and 16 respec-
tively, and the rod 21 connecting said arms
will rock shaft 16, and through arms 26 and 90
27 secured to shafts 22 and 23 respectively,
and rod 28 connecting said arms will rock
the shaft 23. This will compress the boxes
side wise to gather the boxes into a compact
mass preparatory to compressing them. The 95
pin 34 is then removed and the plunger 4
moved downwardly by rotating the screw 5.
As the plunger moves downwardly, the par-
titions collapse, the pieces 11 and 12 sliding
together and serve to keep the boxes in a 100
compact mass.

Having thus described my invention what
I claim is—

1. In a cigar press, in combination with
a base and a plunger, collapsible partitions
slidably mounted on said base and plunger.
2. In a cigar press, in combination with
a base and a plunger having grooves, cross
bars slidably mounted in said grooves, and
collapsible partitions secured to said cross 110
bars.
3. In a cigar press, in combination with a

base and a plunger, collapsible partitions consisting of tongue and grooved pieces secured to said base and plunger.

4. In a cigar press, in combination with a base and a plunger, cross bars slidably secured to said base and plunger, collapsible partitions secured to said cross bars, and mechanism to simultaneously move the cross bars toward or from one another.

5. In a cigar press, in combination with a base and a plunger having grooves therein, angle-iron cross bars slidably mounted in said grooves, and tongue and grooved pieces secured to said cross-bars.

10 6. In a cigar press, in combination with a base and a plunger, cross-bars slidably mounted thereon, rock shafts journaled on the base and plunger, operative connections between said shafts and cross-bars, and collapsible partitions secured to said cross-bars.

15 7. In a cigar press, in combination with a base and a plunger, cross-bars slidably mounted thereon, rock shafts journaled on the base and plunger, operative connections between said shafts and cross-bars to simultaneously actuate said cross bars toward one another, and partitions made of tongue and grooved pieces secured to said cross-bars.

20 8. In a cigar press, in combination with a base and a plunger, cross-bars slidably mounted thereon, rock shafts journaled on said base and plunger, arms secured to said

25 rock shafts, links connecting said cross-bars and arms, other arms secured to said shafts, a rod connecting the last mentioned arms on the shafts journaled on the plunger, and a

rod connecting the last mentioned arms on the shafts journaled on the base, means to 40 actuate the shafts simultaneously, and partitions consisting of interengaging tongue and grooved pieces secured to said cross-bars.

45 9. A cigar press comprising the combination with a base and a plunger having grooves, cross-bars slidably mounted in said grooves, tongue and groove pieces secured to the cross pieces and connecting them in pairs to form collapsible partitions, rock 50 shafts journaled on said base and plunger, arms secured to said rock shafts, links connecting said cross-bars and arms, other arms secured to said shafts, a rod connecting the last mentioned arms on the shafts journaled on the plunger, and a rod connecting the last mentioned arms on the shafts journaled on the base, a lever arm secured to one of the shafts journaled on the plunger and having a slot therein and a transverse hole 55 intersecting the slot, an arm secured to the corresponding shaft journaled on the base, a rod pivotally secured to the last mentioned arm and slidably mounted in the slot in the lever arm, said rod having a series of holes 60 therein, and a pin removably and replaceably secured in the transverse hole in the lever arm and engaging one of the series 65 of holes in the last mentioned rod.

In testimony whereof I hereto affix my 70 signature in the presence of two witnesses.

SOLOMON G. LIPSCHUTZ.
